UNITED STATES PATENT OFFICE

2,019,967

HEAT EXCHANGER

Anthony F. Hoesel, Chicago, Ill.

Application February 11, 1935, Serial No. 5,977

1 Claim. (Cl. 257—255)

The object of the present invention is to provide a cheap and simple means of retaining bracing bars in the slots of fins mounted upon heat exchanger conduits.

5 A further object is the reinforcement of finned coil end plates and especially so at their points of suspension.

In the drawing:

10 Figure 1 is a perspective view of a cooling unit end plate embodying the invention.

Figure 2 is an elevational view of a slotted fin.

Figure 3 is an elevational end view of a cooling unit embodying the invention.

15 Figure 4 is an elevational side view of Figure 3.

Referring to the drawing:

In Figure 1, the plate 1 has slots 2 and holes 3 in its flat portion. Around the outer edges of plate 1 are upturned portions 4. The nearest upturned portion 4 has fold backs 5, through which, 20 and the adjacent portions of the flat portion of the plate 1, holes 6 pass.

In Figure 2, the fin 7 has a bore 8 and slots 9.

25 In Figures 3 and 4, a fluid circuit conduit has a plurality of parallel reaches 10 in banked relationship, the individual parallel reaches being joined by return bends 11, which project through the slots 2 of the end plates 1, defining the end limits of the finned portion of the coil.

30 The parallel reaches 10, have a number of fins 7 mounted thereon and in intimate heat transfer relationship therewith. The slots 9 in the fins 7 frictionally engage bracing bars 12, which ex-

tend beyond the individual end fins of the parallel reaches. The extensions of the bracing bars 12 are embraced by the upturned portions 4 of the end plates 1, thereby retaining the bracing bars 12 in the slots 9 of the fins 7.

5 The bracing bars in the center of the coil are retained within their respective slots due to the nested relationship of the coil.

The holes 6 in the end plates 1 are for the purpose of engaging hanger support means for the 10 assembly.

The upturned portions 4, of the end plates 1, serve as reinforcements, whereby equivalent rigidity may be obtained with a thinner material than could normally be obtained without such reinforcement.

15 While the above is a specific concept of the invention, the spirit and scope of the same is not limited thereto.

I claim:

20 In a heat exchanger assembly comprising a plurality of conduit reaches upon which are mounted a plurality of spaced apart slotted fins, a bracing bar to frictionally engage the slots of the said fins and maintain the said spacing, 25 means engaging the outer edge of the bracing bar to assist the frictional engagement with said fins in the retention of the bracing bar within its associated fin slots, the said means comprising an end plate having flanged portions engaging 30 the bracing bar.

ANTHONY F. HOESEL.
